UNITED STATES PATENT OFFICE.

ARTHUR H. DU GRENIER, OF HAVERHILL, MASSACHUSETTS, ASSIGNOR OF ONE-HALF
TO HAROLD B. WOODS, OF HUDSON, MASSACHUSETTS.

CHECK-CONTROLLED MECHANISM.

Application filed June 20, 1924. Serial No. 721,205.

To all whom it may concern:

Be it known that ARTHUR H. DU GRENIER, a citizen of the United States, and resident of Haverhill, in the county of Essex and

5 State of Massachusetts, has invented an Improvement in Check-Controlled Mechanism, of which the following is a specification.

This invention relates to certain improve-

10 ments in mechanism used in connection with vending machines for testing the coins or checks which are inserted therein, so as to prevent the operation of the machine to deliver the goods in case the coin or check 15 which was inserted does not conform in certain physical characteristics.

In the present instance the invention relates to a mechanism which is more particularly designed to exclude checks which are 20 likely to be placed in the machine in lieu of a cent.

The exclusion of checks which exceed a standard diameter or thickness is usually accomplished at the check entrance, so that it 25 is principally important to provide mechanism for excluding checks which are undersize, and I have ascertained from experience that the checks which are likely to be placed in machines of this character, in lieu of 30 standard cents, and are insertable therein, are of slightly less diameter than the standard diameter of the cent. Also, that if means for testing the diameter of the check which is inserted are provided which are 35 extremely accurate, so that a variation of less than a thousandth of an inch is detected, the result will be that, as a rule, comparatively few checks will be found in the coin receptacle, after it has been in operation 40 for a period, which are not genuine coins. Consequently, while it is also desirable under some conditions to test the check which is inserted as to weight, thickness and magnetism, an accurate test as to 45 diameter is usually sufficient where the check to be inserted is a cent.

As machines which test only as to diameter may sometimes be operated by placing together two celluloid disks of the standard 50 diameter, it is further desirable to provide against operation of the machine by such means. Also, machines of this type, which employ a rotary check carrier having a check receiving recess opening to its periphery, 55 may be operated indefinitely without deliv-

ering the check, by inserting a slightly mutilated or over-size check, unless special means for positively removing it from the recess is provided.

The objects of my present invention are, 60 primarily, to provide a mechanism of the type above referred to which will exclude and return to the purchaser checks which are of only slightly less diameter than the standard diameter of the coin to be inserted, 65 which will act positively to remove a slightly oversize or mutilated check from the carrier and which will exclude a check of half standard thickness or two checks together, the combined thickness of which is equal to 70 standard. Also to provide a mechanism which is of simple construction, so that it may be manufactured at moderate cost, and which may be adjusted without difficulty.

I accomplish these objects in the manner 75 hereinafter described and as illustrated in the accompanying drawings, in which a preferred embodiment of my invention is shown and in which:

Fig. 1 is a front elevation of the outer cas- 80 ing of the apparatus.

Fig. 2 is a rear elevation of the check carrier with the check measuring mechanism removed.

Fig. 3 is a rear elevation of the entire 85 mechanism.

Figs. 4 and 5 are position views of the check carrier.

Fig. 6 is a detail view on an enlarged scale 90 of a portion of the check measuring means.

Figs. 7 and 8 are sectional views at lines 95 $x-x$ and $y-y$, respectively of Fig. 3.

Fig. 9 is a detail sectional view at line 100 $z-z$ of Fig. 3.

In practice, the entire check handling 105 mechanism is mounted on a front plate 1, which is attached to the vending machine in connection with which the apparatus is used, and an operating shaft 2, having a handle 3 on its front end, is provided, said shaft also having a crank arm 4 on its rear end for actuating the bending mechanism when rotated. A spring 5 is coiled about the shaft 2 and is engaged with the arm 4 at one end and with the casing at the other, and acts to return the parts to initial position after they have been actuated. A partition plate 6 is attached to the rear side of the casing and acts to close the rear side of the coin entrance slot 1^a in the front plate. A check 110

carrier 8, which consists of a suitably shaped flat disk of the same thickness as that of the checks to be placed therein, is mounted on the shaft 2 between the front plate 1 and the 5 partition 6, said carrier being provided with a semi-circularly shaped, peripherally disposed check-receiving recess 8^a which, in the initial position of said carrier, is held in register with the check-entrance slot of the 10 front plate, as shown in Fig. 2.

A locking lever 10 is pivotally mounted on the partition 6 by means of a pivot 12 located above the level of shaft 2 near the periphery of the carrier and located in said 15 lever near one end, so that said lever has relatively short and long arms. The long arm has a recess 10^a in its end and is normally held by a spring 14 with its recessed end in the path of movement of a pin 15, 20 mounted in the carrier 8, so that, when the carrier is rotated to an intermediate position in which the checks will still be held thereby, unless the lever 10 is moved from said position, the pin 15 will engage said lever in 25 said recess 10^a and lock said carrier against further operative movement. A measuring lever 16 is also mounted on a pivot 18 in the partition 6 at the right of the check entrance, said pivot being located in said lever 30 16 near one end thereof, so that it has relatively long and short arms, the long arm thereof being provided with a pivot 20 at the end which is located in a slot in the end portion of the short arm of lever 10, so that 35 a form of compound lever is provided. The short arm of lever 16 is provided with a transverse lug 16^a, which is extended at right angles thereto over the edge of the carrier 8, and a check-engaging screw 22 is 40 mounted in said lug in position to engage the rim or edge of a check held in the recess 8^a of said carrier when a diameter of a check carried thereby coincides with the radial line from the axis of shaft 2 to the end of the 45 screw. A lock nut 23 is preferably provided on said screw 22 and the latter is made of hardened steel and has a pointed or conical end.

With the construction as thus far described, in the normal operation of the machine if a check of the size which the apparatus is designed and adjusted to receive is placed in the recess 8^a of the carrier and the handle 3 is turned to the right, the check will 50 be carried in the plane of the carrier towards the screw 22. The movement of the compound levers 10 and 16 by the spring 14 is arrested by the engagement of the lug 16^a with the edge of the partition 6, over which 55 it extends, in which position the lever 10 will be held with its end in the path of movement of the pin 15, and the screw 22 is so adjusted in the lug 16^a that when the carrier 60 is in the position in which the radial line to screw 22 bisects the bottom of the coin re-

cess 8^a. The distance from the middle of said bottom to the tip of the screw is slightly less than the diameter of the standard check, so that the screw will be engaged by the 70 rim of the check a short distance before a diameter of the check is carried into coincidence with the radial line from the axis of the shaft 2 to the pointed end of the screw 22, so that, during the remainder of the movement of the check to this radial position, it will push outward said screw and the arm of lever 16 which supports it, causing the long arm of lever 10 to be swung outward or downward, and, if the screw 22 is properly adjusted and the check which 75 was inserted is of standard diameter, the extent to which said lever 10 will be swung will carry it out of the path of the pin 15, so that the movement of the carrier may be continued and the vending machine to which 80 it is attached will be operated. The pivot 12 of the lever 10 is so located that the end of the lever is swung somewhat in the direction in which the pin 15 is moving and the inner edge of the lever 10 is curved nearly 85 concentrically with the path of movement of said pin, so that the movement of said lever out of intercepting position does not begin until the pin has almost engaged the 90 end of the lever, and then this proximity continues until the movement laterally of this path is sufficient to permit the pin to be carried over the end portion of the lever close to its upper edge, so that by the time 95 the check is pushed past the radial position, and no longer holds the lever 10 out of intercepting position, the pin 15 will prevent the levers from returning to their normal position until it is disengaged therefrom on the return movement.

It will be noted that with the above described arrangement of locking levers, a slight movement of the screw 22 in the short arm of lever 16 causes a greatly amplified movement of the end of the lever 10, so that a difference of movement of less than a thousandth of an inch of the screw will be sufficient to move the end of the lever 10 from a position in which it intercepts the pin 15 and locks the mechanism against further operation movement, to a position in which the pin will be permitted to pass and unlock the mechanism. In other words, if the diameter of the check which is inserted is only very slightly less than the standard 115 diameter, the mechanism cannot be operated to deliver the goods, and, on release of the handle 2 the carrier will return the check to the position it was in when first inserted, so that it may be recovered.

The particular lever arrangement above described is of special advantage in the connection shown. It is of vital importance that any variations in diameter of the checks be amplified to the greatest extent prac-

ticable, so that any check which is slightly under size will fail to operate the machine. It is also necessary to provide an intercepting means which is very strong and capable of withstanding blows of considerable force, for the reason that when a purchaser finds that the check does not unlock the carrier he is liable to try and force the carrier past the lock. With the arrangement shown the 5 pin 15 may be made sufficiently strong to withstand all blows to which it is likely to be subjected and the lever 10 which it engages may likewise be made sufficiently heavy for the purpose and wide enough at 10 the end which is engaged to withstand the severe blows to which it is likely to be subjected, and to prevent the pin from passing the end of said lever unless the latter is swung laterally through a considerable distance. The space available for the location 15 of the locking means is practically limited to the space within the casing which encloses the check carrier and by pivoting the levers 10 and 16 adjacent the rim of the carrier and extending them in proximity to 20 said rim the space available for said levers is effectively utilized, and a maximum motion of the locking portion is secured for 25 a slight movement of the check engaging 30 means.

To prevent operation of the machine by two thin disks or checks of standard diameter, but of half the standard thickness, one half 8^b of the bottom of the recess 8^a is 35 recessed to a slightly greater depth than the other half and the screw 22 is located slightly to one side of the middle of the position in which the standard check is held, as shown in Fig. 6, so if two thin disks are 40 placed in the machine only one will be engaged by the end of screw 22 and this one will not be supported in the same relation thereto as the other on account of the recessed bottom of the recess 8^a, and as a result 45 the lever 10 will not be moved out of locking position, as shown in Fig. 5.

The partition 6 is provided with a passage 24 through which the check is to be discharged into a coin receptacle near the end 50 of the operation. The check recess 8^a is of a size that a standard coin fits closely therein, so that if a coin has been mutilated so as to increase its diameter slightly, or if a check of slightly greater diameter than the standard is forced into said recess, it is likely 55 to become wedged therein, and will not fall therefrom by gravity, through opening 24 under such conditions unless positively acting means is provided for removing the 60 check from the carrier, when the check is carried to the position where it should be discharged therefrom, it will remain in the recess 8^a and be returned to the vendee, after the goods had been delivered, so that 65 it would be possible to operate the machine

indefinitely with the same check. To prevent such an occurrence, a pointed finger or dog 25 is provided, which is pivotally mounted on the partition 6 at the edge of the passage 24 in position to extend through 70 said passage and rest on the back side of the carrier against which it is held by a spring 26. The carrier is provided with a slot 8^c, which opens to the recess 8^a and the front plate or casing is provided with a recess 1^c 75 on its rear side in position to receive the pointed end of the dog 25.

With this arrangement, as the carrier moves towards the position in which it is to deliver the check, the pointed end of dog 25 will be swung through the slot 8^c and into the recess 1^c, so that, as the movement is continued the check will be carried into engagement with the inclined surface provided by the edge of the dog 25 and will thus be deflected inward and dislodged from the carrier recess 8^a, so that it will be free to pass through the passage 24, as indicated in Fig. 9. With this arrangement it will thus be impossible to operate the apparatus to deliver the goods, without delivering the check to the money receptacle. 80 90

A spring actuated dog 27 is mounted on the casing in position to engage ratchet teeth 8^d on the carrier to prevent return 95 movement of the carrier before the delivery movement is completed. A washer interceptor is also provided which comprises a pivoted spring actuated pawl 28, the end of which is arranged to rest on the surface of the check as the check is carried past the pawl, so that, if there should be a hole in the middle portion of the check, the end portion of the pawl will enter the hole, and thereby prevent further operative movement 100 of the carrier. 105

With the above described construction means are provided whereby the check is accurately tested as to diameter and will not permit operation of the apparatus to deliver the goods unless the check is of full standard size, also means permitting ready and accurate adjustment to the standard diameter is provided, and means whereby a thin disk of standard diameter will be 110 returned without permitting operation of the machine. The construction is simple and durable and is well adapted to withstand the abuse, as well as the ordinary use, to which an unprotected vending machine 115 120 is likely to be subjected. 125

I claim:

1. In a check-controlled mechanism, a check-carrier comprising a rotatably mounted disk having an abutment and a peripheral 125 check-receiving recess and operatively movable to carry a check therein from a receiving to a delivering position, a locking lever having means for normally holding one arm thereof in position to be engaged 130

by said abutment to lock said carrier against operative movement at a point intermediate said positions, a supplemental lever engaged with said locking lever and having one arm thereof extending transversely of the outer periphery of the path of movement of the checks, said arm having an adjusting screw therein arranged to extend normally into said path and to be moved therefrom by the 10 check to move said locking lever out of locking position.

2. In a check controlled mechanism, a check carrier movable between check-receiving and delivering positions and consisting 15 of a rotatably mounted disk of a thickness equal to the standard thickness of the check and having an abutment and a check receiving recess opening inwardly from the rim, one side portion of said recess being 20 of greater depth than the other side portion to permit a check of less thickness than the standard to be supported on the bottom of the portion of greater depth, a locking device normally disposed in position to be engaged by said abutment to obstruct operative movement of the carrier beyond a point intermediate said positions, actuating means for said locking device having check engaging means arranged to project normally 25 into the path of movement of the check at the outer periphery thereof, in the plane of movement of the deeper portion of said recess and at one side of the plane of movement of the other portion thereof, said engaging means being positioned with relation to the bottom of the portion of the recess of less depth, to move said locking device out of obstructing position as the check 30 engaging means is forced outward by a 40 check of standard dimensions.

3. In a check controlled mechanism, a disk-shaped check carrier having a lateral projection adjacent its rim and a check receiving recess in its rim portion, said carrier being movable about a central axis to 45 carry a check in said recess from a receiving to a delivering position, a locking lever having a long and a relatively short arm

and means to hold the same with the end portion of its long arm in position to be 50 engaged by said projection to lock the carrier against operative movement between its receiving and discharging position, a measuring lever having a long arm engaged with the short arm of said locking lever and a 55 relatively short arm having an end portion thereof normally extending into the path of movement of the check as it is carried in said recess in position to be engaged by the rim of the check at points diametrically opposite the bottom of said recess, said levers being extended continuously with each other adjacent the rim of the carrier throughout the lengths thereof in position to permit the long arm of said locking lever to be swung 60 to one side of the path of movement of said projection.

4. In a check-controlled mechanism, a check-carrier comprising a rotatably mounted disk having an abutment and a peripheral 70 check-receiving recess and operatively movable to carry a check therein from a receiving to a delivering position, a lever pivotally mounted at one side of said carrier to swing in parallel relation thereto and having a long and a relatively short arm, means 75 normally disposed in position to be engaged by said abutment to lock said carrier against operative movement at a point intermediate said positions, said means being movable by 80 said long arm to an inoperative position upon normal actuation of said lever, said short arm having a portion thereof extending transversely of the outer periphery of the path of movement of the check when 85 carried by said carrier and an adjusting screw threaded in its said arm portion in radial relation to the carrier and having its inner end portion normally projecting into 90 said path in position to be moved therefrom by engagement with the rim of the check when carried past the same and cause normal actuation of said lever.

In testimony whereof, I have signed my name to this specification.

ARTHUR H. DU GRENIER.
